UNITED STATES PATENT OFFICE.

ALPHONSO S. COMSTOCK, OF EVANSTON, ILLINOIS.

CARBURETER.

1,064,445.

Specification of Letters Patent. Patented June 10, 1913.

Application filed February 26, 1912. Serial No. 680,039.

To all whom it may concern:

Be it known that I, ALPHONSO S. Comstock, a citizen of the United States, and resident of Evanston, county of Cook, and State of Illinois, have invented certain new and useful Improvements in Carbureters, of which the following is a specification, and which are illustrated in the accompanying drawings, forming a part thereof.

10 The invention relates to carbureters especially adapted for use in connection with internal combustion engines employing as a fuel a fluid such as gasolene, the carbureter being of the type provided with a regulated 15 air-intake port controlled by a valve mechanism which responds to the demands of the engine.

The objects of the invention are to provide in a carbureter of this type a more sensitive automatic valve mechanism for the air-intake port than has heretofore been proposed and to provide means for manually controlling the available area of the air port in question.

25 The invention consists of a structure such as hereinafter described and which is illustrated in the accompanying drawings, in which—

Figure 1 is a vertical central section of the 30 carbureter embodying the invention; Fig. 2 is a plan view of the same; and Fig. 3 is a detail, partly in section, of an automobile showing the improved carbureter mounted thereon.

35 In carbureters of the type shown in the drawings there is provided a constantly open passage for the admission of air, into which the fuel is delivered from a suitable nipple; and a supplemental air port controlled by an 40 automatically closed inwardly opening valve. When the engine throttle is but slightly open the suction is satisfied through the constantly open passage, the pull being sufficient to draw from the nipple the requisite 45 fuel supply to properly proportion the mixture. When the throttle is open to a greater extent the suction becomes stronger in the vacuum chamber of the carbureter and in consequence unless an auxiliary air port be 50 provided the proportion of fuel to the volume of air which can enter through the constantly open passage will be increased and the mixture will become too rich.

55 Great difficulty has been experienced in controlling the valve of the auxiliary air port in order to make it effective throughout

the entire range of variations in the demands of the engine. It is essential that the valve be held to its seat by means of a spring of considerable tension in order not only that it may not yield too easily to suction, but that it will promptly close the valve when the suction is satisfied; and furthermore that it will prevent chattering of the valve under the jarring influences of a rough road when the engine is mounted on an automobile.

The valve is necessarily of greater area than its seat in order that it may completely close the port. The effective area of the valve, when closed, to which the external atmospheric pressure is applied when a minus pressure is created within the vacuum chamber of the carbureter, is of course the cross sectional area of the air port. As soon as the valve leaves its seat its entire surface area is acted upon by the external pressure. The potential difference therefore between the spring pressure and the pressure developed by suction is greater when the valve is closed than when it is open and in consequence the valve is reluctant to move in either direction. This sluggish action unfavorably affects the action of the carbureter to a greater extent when the throttle is partially open, that is to say, when it is open but little beyond its minimum opening, than when it is wide open. When the throttle is fully open the suction is ample to move the auxiliary valve from its seat and there is no difficulty in securing a properly proportioned admixture of air and fuel under such circumstances. With the throttle at its medium positions, however, if the spring of the auxiliary valve have sufficient tension to prevent chattering and secure prompt closure the valve will not open as promptly as it should and as a result the suction must be satisfied to too great an extent through the constantly open air passage, and as the suction here applied acts also upon the nipple the quantity of fuel introduced is relatively too large. Under such conditions the engine is not only operated uneconomically but it becomes fouled with carbon as the fuel is not completely burned. I have overcome these difficulties by providing a diaphragm which yields to the suction within the vacuum chamber of the carbureter and is mechanically connected with the auxiliary valve so as to apply opening pressure thereto. As the diaphragm

may have a much larger area than the valve the latter may be provided with a sufficiently strong spring to normally hold it firmly to its seat and to promptly close it as the engine suction is satisfied, while the diaphragm applies sufficient power to promptly open the valve even though the throttle may be open to only a moderate extent. When the throttle is opened to the minimum extent at which the engine can be operated the suction in the vacuum chamber of the carbureter is fully and promptly satisfied through the constantly open air passage and without drawing in an undue proportion of fuel. As the throttle opens so as to increase the suction within the vacuum chamber to such an extent that the proportion of fuel would be otherwise unduly increased, the auxiliary valve is opened by the action of the diaphragm and a proper balance between the air and fuel supply is thereby maintained. This regulation is effective throughout the entire range in the variation of the demands of the engine upon the carbureter and by reason of the increased power which is available through the diaphragm for opening the valve a nice adjustment becomes possible which gives a perfectly satisfactory action under all conditions except where there is a considerable variation in load and except when in cold weather it becomes necessary to use an excessive quantity of fuel when the engine is first started because of the failure of the fuel to completely vaporize until the engine becomes heated. These difficulties which are not taken care of by the action of the diaphragm I have overcome by providing a manually controlled valve for the auxiliary air port and located on the atmospheric side of the auxiliary valve, this regulating valve being provided with a controlling handle within easy reach of the operator. When therefore the load is materially increased, as by the climbing of a hill, and it becomes necessary to use a richer explosive mixture the operator may partially close the auxiliary air port thus increasing the suction applied to the fuel nipple. In starting the engine he may entirely close the auxiliary port and thus relatively increase the proportion of fuel employed, enabling him not only to more easily start his engine when the weather is cold but also to drive his car as soon as the engine is started. As the engine becomes warm the auxiliary air port may be operated. The operator is thus provided with means directly under his control for properly regulating the mixture for running his engine.

The carbureter shown in the drawings is of a type in common use and comprising a body portion 10, inclosing a vacuum chamber 11, a bowl 12 for containing the immediate supply of liquid fuel, this bowl being

provided with a nipple 13 to which may be attached a pipe (not shown) leading from a storage tank, the induction passage 14 for the liquid being controlled by a gravity-seating valve 15, and the level of the liquid in the bowl being determined by a float 16 carried by a lever 17, pivoted, as shown at 18, and having a backwardly-extending arm 19 for forcing the valve 15 to its seat when the float is raised by the liquid reaching the maximum level intended to be attained within the bowl.

An air duct 20 leads upwardly through the bowl 12, its lower end, shown at 21, being open. A nipple 22 is located within the duct 20 and opens upwardly, and is connected by a suitable duct 23 with the chamber of the bowl 12. The upper end of the nipple 22 is a little above the level to which the liquid is permitted to rise by the float. A needle valve 24 fits within the open end of the nipple 22, and is adjustably controlled by a stem 25 entering through the top wall of the body 10 and in threaded engagement therewith, and carrying at its outer end a thumb-nut 26. A nipple 27 leads from the chamber 11 and affords means for connecting this chamber with the cylinders of the engine (not shown). A throttle valve 28 is located at the outlet of the chamber 12 leading to the nipple 27, and is controlled by means of a lever-arm 29.

An auxiliary air inlet is shown at 30, and is automatically controlled by means of a valve 31, provided with a stem 32 reciprocating through a cap 33, and carrying a helical spring 34 reacting between the cap and an adjustable nut 35 upon the stem, this spring normally holding the valve to its seat, and its tension being regulated by the adjustment of the nut.

As thus described the carbureter is of common form, except that the air induction ports 43 enter the inlet passage 30 laterally. Its parts may be variously arranged, but in practice are related substantially as described. The suction of the engine draws in air through the passages 20 and 30 and liquid from the nipple 22, the volume being controlled by the throttle valve 28. The carbureter as illustrated provides for a set adjustment of the fuel-controlling valve 24, but the invention as hereinafter described is applicable also to carbureters of this type in which provision is made for varying the adjustment of the valve with the movement of the throttle valve.

In this type of carbureters difficulty has been encountered in so adjusting the regulating valve mechanism of the supplemental air inlet 30 as to adapt it to the requirement of the engine when running at various speeds. It is essential that this valve mechanism be sensitive to the suction of the engine, and the trouble has been to secure

such sensitiveness as will render the valve useful at moderate speeds without making its controlling spring too rigid to yield to the light suction felt in the chamber 11 when the throttle valve is nearly closed. In order to render the valve more sensitive, a flexible diaphragm 36 is mounted in a suitable casing 37, in communication, through the medium of a duct 38, with the chamber 11 below the valve 31. A stem 39, attached to the diaphragm, is pivotally connected with a lever arm 40, pivoted to an arm 41 of the casing 37, its free end 42 bearing upon the end of the stem 32.

15. Suction within the chamber 11 is applied not only to the valve 31 but also to the diaphragm 36 to cause the valve to open. The tension of the spring 34 is so adjusted that when the throttle 28 is closed to provide the engine with its minimum charge the suction within the chamber 11 will not be sufficient to open the valve 31, and this suction is accordingly satisfied by the inflow of air and liquid through the passage 20.

20. Upon the opening of the throttle to gradually increase the charge, an additional supply of air is required in order that the increased suction shall not act too strongly upon the fluid nipple and render the charge 25 too rich. This additional air supply is secured through the passage 30, the valve being opened by the action of the suction directly upon the valve and upon the much larger area of the diaphragm. When the 30. throttle is more widely opened, to run the engine at higher speeds, the valve 31 is open substantially all the time and the suction in the chamber 11 is sufficient to insure an ample supply of liquid.

35. The valve for manually controlling the induction ports 43 is here shown as taking the form of a ring 44 encircling the upper end of the nipple through which the passage 30 enters the vacuum chamber, and being 40. rotatable thereon. The ring 44 is provided with apertures 45 of the same size and number as the ports 43, these apertures and ports being circumferentially spaced a sufficient distance so that the ring may be 45. turned to bring the ports and apertures out of register, thus providing for the regulation of the port areas as may be desired. The ring 44 is provided with a radially projecting arm 46 from which a link 47 leads to a 50. hand lever 48 so located as to be within

easy reach of the operator. As shown, the hand lever 48 is pivotally attached to a part of the dash board of an automobile but its position may be changed as desired and any suitable system of levers or links may be 55. substituted for the single link 47 according to the judgment of the builder. By the movement of the lever 48 the ring 44 may be shifted in order to open the ports 43 as much as may be desired. 60

65. I claim as my invention—

1. In a carbureter, in combination, a vacuum chamber, an air induction port and a fuel induction port open to such chamber, an auxiliary air port open to the vacuum chamber, a manually controllable regulating valve for the last named port, a normally closed valve in said port, a diaphragm directly responsive to the lowering of pressure in the vacuum chamber, a stem supported by the diaphragm, and a lever fulcrumed upon a fixed support and operatively connected with the stem and having a bearing on the valve in opposition to its closing means. 70

75. 2. In a carbureter, in combination, a vacuum chamber, an air induction port and a fuel induction port open to such chamber, an auxiliary air port open to the vacuum chamber, a manually controllable regulating valve for the last named port, a normally closed valve in said port, a diaphragm directly responsive to the lowering of pressure in the vacuum chamber, a stem supported by 80. the diaphragm, a lever fulcrumed upon a fixed support and operatively connected with the stem and having a bearing on the valve in opposition to its closing means and 85. means for shifting the fulcrum of the lever. 90

95. 3. In a carbureter, in combination, a vacuum chamber, an air induction port and a fuel induction port open to such chamber, an auxiliary air port open to the vacuum chamber, a normally closed valve in said port, a diaphragm directly responsive to the lowering of pressure in the vacuum chamber, a stem supported by the diaphragm, and a lever fulcrumed upon a fixed support and operatively connected with the stem and having a bearing on the valve in opposition to its closing means. 100
